UNITED STATES PATENT OFFICE

ALBERT P. HODGE, OF WINSTED, CONNECTICUT, ASSIGNOR TO WILLIAM L. GILBERT CLOCK COMPANY, OF WINSTED, CONNECTICUT, A CORPORATION OF CONNECTICUT

COMBINED TIME AND COIN CONTROLLED APPARATUS

Application filed April 26, 1929. Serial No. 353,392.

The present invention relates to improvements in combined time and coin controlled apparatus, and more particularly refers to an improved apparatus, wherein a certain 5 performance may be continued over a given interval of time upon the deposit of a coin of predetermined denomination.

An object of the invention is to provide certain improvements in the time controlled 10 mechanism, whereby the performance will be interrupted positively and faithfully at the end of the interval paid for.

Another object of the invention resides in providing certain improvements in the coin 15 controlled apparatus which provides for the deposit simultaneously of a plurality of coins, and the mechanism is so coordinated and arranged that the coins will be fed through the coin apparatus singly, whereby 20 to continue the performance in a substantially uninterrupted sequence from one time period to the other.

A further object of the invention resides in providing a coordinate coin controlled 25 apparatus and time controlled mechanism, wherein the parts are grouped and inter-coupled for unified operation, whereby the deposit of a proper coin will set the time controlled mechanism into operation and will 30 start the performance, and the time controlled mechanism will automatically suspend operations and stop the performance after the elapsed time paid for.

With the foregoing and other objects in 35 view, the invention will be more fully described hereinafter, and will be more particularly pointed out in the claims appended hereto.

In the drawings, wherein like symbols refer 40 to like or corresponding parts throughout the several views,

Figure 1 is an elevation of a time controlled mechanism and cooperating coin controlled apparatus constructed according to 45 the present invention and shown in the closed or operating position.

Figure 2 is a similar view with parts shown in the open or non-working position.

Figure 3 is a longitudinal sectional view,

with parts shown in elevation, of the time controlled mechanism.

Figure 4 is a plan view of the time controlled discs.

Figure 5 is a side view of a spring employed, and 55

Figure 6 is an edge view of the spring and fragmentary section through the cooperating discs.

Figure 7 is a detail view of the coin chute 60 showing the insulation means for supporting the contacts.

Referring more particularly to the drawings, 10 designates generally a coin chute with the coins 11 therein. This coin chute 65

is provided with spaced insulated contacts 12 and 13 which may form sections of the chute. The contacts 12 and 13 are in a circuit 14, 15 with an electromagnet 16 of the time controlled mechanism designated generally at 70

17. Coin arresting fingers 18 and 19 are adapted to project into the coin chute in the path of the coins 11. These fingers are carried by a lever 20 fulcrumed at 21. The 75

fingers are so disposed relatively to one another that only one finger at a time may be projected into the path of the coins in the coin chute; and one finger lies above the insulated contacts 12 and 13, the other finger being located just below said contacts. A coil 80

spring 21 is connected to the lever 20 and to a fixed stud and acts yieldingly to bias the lever 20 to the position shown in Figure 2 in which the finger 19 is out of the chute and the finger 18 projects into the chute. A bell crank 85

lever 22, fulcrumed at 23 is adapted to bear against the lever 20 for the purpose of shifting said lever to the position shown in Figure 1.

This bell crank lever is adapted to be moved by engagement of an arm 24 operated by the time controlled mechanism, this arm 24 constituting the armature of the electro-magnet 16. The arm 24 is carried by one branch 25 of a substantially L-shaped lever, the other branch of which is designated at 26. The 90

lever is fulcrumed at 27 and carries a projection 28 extending outwardly from the plane of the lever and positioned to engage the notches 29 of a disc or wheel 30. This disc or 95

100

wheel 30 cooperates with a companion disc or wheel 31, preferably of smaller diameter.

Referring more particularly to Figure 3, the two discs are shown as mounted on a bearing member 32 having the stepped surface 33 on which the disc 30 is loosely mounted and the second stepped surface 34 on which the companion disc 31 is fixedly mounted. The bearing member 32 is fixedly mounted upon a shaft 35 which is driven by the clock-work or time controlled mechanism 17. In one face of the disc 30 there is made a recess 36 to receive a circular or other form of spring 37 having the out-turned ends 38 and 39 as shown in Figure 6 fitting into sockets 40 and 41 made respectively in the discs 30 and 31. The lever 26 carries at its upper end a spring or resilient member 42, preferably having its intermediate portion looped, as indicated at 43 to increase the resilient tension of the free arm 44.

This arm 44 is adapted to engage the balance wheel 45 of the time controlled mechanism. The balance wheel is associated, in the customary manner with the escapement 46. The other portion of the time controlled mechanism, may be the usual clock-work train and the shaft 35 may carry the minute hand or be connected with the arbor that carries such hand.

The notches 29 in the disc 30 may be disposed at quadrants or at 90° from one another, in which case they represent fifteen minute intervals. It will be understood, however, that the notches 29 may be angularly displaced on the periphery of the disc 30 in any desired way. The branch 25 of the lever 26 carries also an insulating block 47 for engaging beneath a switch contact 48, the other contact of which is indicated at 49. The contacts 48 and 49 are in the circuit indicated at 50 and 51, which is the performance circuit, and is adapted to do the work, whatever it may be. For instance, the circuit wires 50 and 51 may be connected to a radio circuit.

In operation, the parts are normally in the position shown in Figure 2. If we assume that there is no coin in the chute 10, then the coil spring 21 will draw the lever 20 over so that the finger 18 below the contacts 12 and 13 is projected into the chute, while the upper finger 19 is withdrawn.

This action of the spring 21 in drawing the lever 20 over to the right, will act through the bell crank 22 to lift the armature 24 and in so doing to swing the lever 26 to the position shown in Figure 2, in which the projection 28 of said lever enters the notch 29 of the disc 30 which is presented to it.

In Figure 2 the spring stop arm 44 is shown as engaging the balance wheel 45, which acts to arrest the movement of the time controlled mechanism. The block 47 is also swung down so that the spring contact

70 fingers 48 and 49 will be separated, it being understood that these spring fingers are biased to an open position. As a consequence the work circuit 50, 51 is dead and the apparatus awaits the insertion of a coin of the selected denomination in the chute 10. Upon the insertion of such coin, the coin will descend to the position shown by the lowermost coin in Figure 2. In other words the coin will fall until its progress is arrested by the lower stop finger 18, which is so positioned that it will hold the coin bridging the insulated contacts 12 and 13, and a circuit 14, 15 will be closed through the coin and through the electro-magnet 16. The electro-magnet will attract the armature 24, thus vibrating the bell crank lever 22 and the lever 20 to the position shown in Figure 1, the finger 18 being withdrawn from the coin chute and the coin being released and dropped down the chute to a proper coin depository below.

75 At the same time the upper finger 19 is brought into the chute so that coins above will be withheld. When the electro-magnet draws the armature 24 down, it closes the work circuit through the block 47 engaging the spring contact arm 48 of the switch and the radio will be energized and begin its performance. At the same time the spring stop arm 44 is withdrawn from the balance wheel 45 and the clock-work mechanism will immediately begin to work, thus driving positively the disc 31 through the shaft 35 and yieldably the companion notched disc 30 through the spring connection 37.

80 100 As the notched disc 30 rotates, the projection 28 of the lever 26 will ride over the blank periphery of the disc 30 between adjacent notches 29 and the parts will thus be retained in the position shown in Figure 1, until a predetermined time interval has elapsed, which interval is represented by the angular distance between adjacent notches 29. This angular distance may be varied as desired to suit the requirements of the work circuit.

105 110 As shown the clock-work mechanism will continue for a period of one-quarter of an hour, whereupon the next notch 29 is presented to the projection 28. When this occurs the coil spring 21 will act through the levers 20, 22 and armature 24 upon the lever 26, thus moving all of these parts to the position shown in Figure 2 and permitting the switch contacts 48 and 49 to spring apart thus opening the work circuit 50 and 51 and suspending the performance of the radio or other apparatus.

115 120 Now it has been found inconvenient to repeat the insertion of coins at the expiration of each time interval. For instance, in restaurants diners are obliged to get up from the table each time the performance stops to insert an additional coin if they care for a continuance of the entertainment. The sus-

pension of the performance or entertainment at the end of short intervals is also very undesirable in connection with alternating current radio receiving sets, because of the fact 5 that the tubes cool and time is involved in the reheating of the tubes before the performance can be continued and a certain amount of the performance is lost which destroys the continuity of the entertainment.

10 For these and other reasons, the present apparatus is so constructed that a patron may in one trip to the machine deposit a plurality of coins to cover any multiple of the time interval of the apparatus.

15 In Figure 2 three coins are shown in the chute which would continue the performance for three-quarters of an hour in accordance with the distribution of the notches 29 shown in the embodiment of the drawings. The

20 action of the apparatus in response to the placing of a single coin in the slot has already been described.

It might further be said, in explanation of the repeated action of several coins, that 25 when the notch 29 is presented to the projection 28 and the projection enters that notch, accompanied by the swinging of the lever 26 to the position shown in Figure 2, and while the disc 30 is thereupon rigidly held 30 against any further rotary movement, there will be a certain lag between the discs 30 and 31 before the clock-work mechanism can be stopped by the frictional engagement of the balance wheel 45 by the spring arm 44.

35 In other words the disc 31, which is positively driven by the clock-work mechanism will continue to rotate a small angular distance even after the companion disc 30 has been completely stopped. This relative angular lag is permitted by reason of the fact 40 that the disc 30 is only loosely mounted on the bearing member 32 and it is only driven from the disc 31 through the spring 37, which will be wound to an extent proportional to 45 the relative angular movement between the discs, and will thereby become endowed with sufficient potential energy to impart to the disc 30 a quick short rotary movement, taking up such lag, as soon as the projection 28 is withdrawn from the notch 29, as by the 50 action of another coin 11 in the coin chute.

Otherwise as soon as the coin was freed, which would happen rapidly, the spring 21 would tend to bring the projection 28 back into the same notch 29 from which it had so recently been lifted. This quick short rotary movement of the disc 30 by the action of the coil spring 37 is sufficient to remove the notch 29 from the path of the projection 28, so that once the lever 26 is swung out to the position shown in Figure 1, the notch 29 will have escaped from the projection 28 and the blank rim of the disc 30 will present itself to the projection 28 no matter how quickly that projection may attempt to enter the

notch. This will insure the continuance of the performance for which the patron has paid by the deposit of his coin. Now when the first coin has dropped through after closing the circuit through the electro-magnet 16 and starting the first performance, that is placing the various parts in the position shown in Figure 1, the finger 19 will hold the other coins in the coin chute above the contacts 12 and 13 and the spring 21 will be held inoperative because of the engagement of the projection 28 with the rim of the disc 30. The position of the parts shown in Figure 1 is, therefore, assured until the next notch 29 of disc 30 appears before the projection 28, whereupon the spring 21 will become active forcing the projection 28 into the presented notch 29 and moving all of the parts to the position shown in Figure 2.

The coins will now descend to the position, shown in Figure 2, the upper finger 19 having been withdrawn from the coin chute. The lower finger 18 will, of course, be thrust in to hold the next lowermost coin across the contacts 12 and 13 for an appreciable time necessary to close the circuit through the electro-magnet 16 and restore the parts to the position shown in Figure 1. Other coins above will act in the same way and the action of the coins will be instantaneous on the mechanism, so that the switch 48, 49 will only be closed momentarily and there will be substantial continuity of the radio or other performance or entertainment.

It is obvious that various changes and modifications may be made in the details of construction and design of the above specifically described embodiment of this invention without departing from the spirit thereof, such changes and modifications being restricted only by the scope of the following claim.

I claim as my invention:

1. In an apparatus of the character described, a time-controlled mechanism, a member positively driven thereby, a companion member yieldingly driven by said first member, a locking device adapted to be held by said second member in operated position for successive predetermined intervals of time, said device and second member having interengaging locking means for locking said second member against movement after the lapse of each interval of time, and coin-controlled mechanism for withdrawing said locking means.

2. In an apparatus of the character described, a time-controlled mechanism, a member driven thereby, a device adapted to be held by said member in locking position for successive predetermined intervals of time, said member and device having interengaging locking means whereby said device holds said member against rotation after the lapse of each interval of time, coin-controlled

means for withdrawing said device from locking position, and means between said time-controlled mechanism and said member whereby the latter is automatically moved forwardly when said device is released therefrom so as to prevent said device from again locking said member in the same position.

3. In an apparatus of the character described, a time-controlled mechanism, a notched disk driven thereby, means between said mechanism and disk for throwing the latter forwardly of said mechanism when said disk is released, a device adapted to engage against the periphery of said disk between said notches whereby said device is held by said disk in operative position for successive intervals of time, said device having a projection adapted to engage in said notches whereby to arrest the movement of said disk, and coin-controlled means to release said device from locking position.

4. In an apparatus of the character described, a time-controlled mechanism, a notched disk, a resilient connection between said mechanism and disk, a device adapted to engage against the periphery of said disk between said notches whereby said device is held in operated position for successive intervals of time, said device having a projection adapted to engage in said notches whereby to arrest the movement of said disk and to place said resilient connection under tension, and coin-controlled means for releasing said device from locking position.

5. In an apparatus of the character described, a time-controlled mechanism, a notched disk driven thereby, a resilient connection between said mechanism and disk, a locking device adapted to engage the periphery of said disk between said notches whereby said device is held in operated position for successive predetermined intervals of time, said device having a projection adapted to engage in the respective notches whereby to arrest the movement of the disk and to place said resilient connection under tension, and coin-controlled mechanism adapted to receive and hold a plurality of coins, and means operated by the successive coins when they reach a predetermined position for releasing said device from said disk, said coin-controlled mechanism having means for successively and singly feeding the coins therein past said position upon each locking movement of said device.

6. In an apparatus of the character described, a time-controlled mechanism, a disk rotatable therewith, a second notched disk, resilient driving means between said disks, a device adapted to engage the periphery of said second disk between the notches thereof whereby said device is held in operated position for successive intervals of time, said device having a projection to enter the notches

of said disk whereby to arrest the movement of the disk and place said connection under tension, said device having means adapted to stop said time-controlled mechanism when said projection enters into a notch, and coin-controlled means for moving said device from locking position.

7. In an apparatus of the character described, a time-controlled mechanism, a disk driven thereby, a second disk having notches, a yielding connection between said disks, a lever having a projection adapted to engage said second disk between said notches whereby said lever is held in operative position for successive predetermined intervals of time, said projection being adapted to enter said notches to arrest the movement of said second disk, a magnet for moving said lever to operative position, and a coin-controlled mechanism for controlling said magnet.

8. In an apparatus of the character described, a clock mechanism, a notched disk driven thereby, a resilient connection between said clock mechanism and disk, a pivoted lever having a projection adapted to engage the periphery of said disk between said notches whereby said lever is held in operated position for successive predetermined intervals of time, said projection being adapted to enter a notch upon the lapse of each interval of time, a switch controlled by said lever, a coin-controlled mechanism having a chute provided with spaced contacts adapted to be bridged by a coin in the chute, an electric magnet in circuit with said contacts, an armature for said magnet carried by said lever, said coin-controlled mechanism having connected coin arresting fingers positioned to be alternately projected into the chute above and below said contacts, a spring normally holding the finger above said contacts out of said chute and the finger below said contacts in said chute, and a connection between said armature and said fingers for reversing the position of said fingers when said lever is in operated position.

9. In an apparatus of the character described, a time controlled mechanism, a member driven thereby, a locking device adapted to be held out of locking position by said member for successive predetermined intervals of time, said device and said member having interengaging locking means for locking said member against movement after the lapse of each interval of time, coin controlled mechanism for withdrawing said locking device from locking position, and means to produce relative movement between the locking device and the member to prevent immediate re-engagement of the locking means after disengagement thereof.

ALBERT P. HODGE.
